UNITED STATES PATENT OFFICE.

JACOBUS HENNEVELD, OF ZAANDAM, NETHERLANDS.

MACHINE GUN.

Application filed November 4, 1926, Serial No. 146,140, and in the Netherlands March 16, 1926.

The invention, hereinafter described, relates in part to tripod mounts for machine guns and, further, to machine guns with which are used straps adapted to pass about 5 the backs of men to enable them to more easily move the gun in different directions.

Hitherto a pair of straps or the like have been attached to light frames which support the gun; the frames being secured to a 10 substantial support.

In instances when tripods or the like have been used for machine guns, the legs have had hinged to their lower ends plates or the like adapted to rest firmly upon the ground 15 and having spurs of just sufficient length to prevent the plates from slipping over the surface.

The object of this invention is to provide a support which, although of light tripod 20 type and about the height of a man of ordinary stature, will be rendered sufficiently rigid to withstand the weight of a man leaning against a strap which, in this instance, is directly or indirectly secured to the gun, 25 thus, for the sake of lightness, dispensing with a gun frame or frames.

Having the object, above referred to, in view, the invention consists in the provision 30 of a tripod having a support from which the legs diverge and to which the gun is pivoted, but which centrally disposed support is, itself, adapted to be inserted into the ground and is provided with an encompassing plate to rest upon the surface of the 35 ground whilst each of the legs has hinged thereto a spade-like plate adapted to be forced, at an advantageous angle, deeply into the ground to resist upward strain; the gun, to be used with the tripod, having a 40 strap at its rear portion, preferably secured to a rearwardly extending rod thereon.

The drawing illustrates, by way of example, means in accordance with the invention.

On the drawing, 1 is the central support 45 which is driven into the ground so far that the ground plate 2 rests on the surface thereof. Hinged to the upper end of the central support are the telescopic legs 3, each having hinged thereto, at its lower end, a spade-like plate 4, adapted to be forced into the ground in a transverse direction. These plates are very efficient means for immobilizing the stand.

The central support 1 is provided, above 55 the pivots of the legs 3, with a crosshead 5 adapted for rotation about the central tube, and, itself, provided with a horizontal pivot 6 for the gun 7. Secured to the rear end of the gun are two handles 8 (one of which 60 is shown) and a rod 9, to which the trace 10 can be attached.

The gunner passes the trace 10 around his body under the arms, takes hold of the handles 8 and points with the aid of the sight, 65 leaning back so as to be supported by the trace and exerting a certain amount of pressure against the rod 9, whereby he can easily keep the line of sight on (or in front of) the moving object.

What I claim is:—

1. A machine gun comprising a gun and a support therefor, said support comprising a tripod having telescopic legs, hinged spade-like members provided at the lower ends 75 of said legs and adapted to be forced into the ground at an angle so as to resist upward strain, a central stem adapted for insertion into the ground and from which the tripod legs diverge, and an encompassing plate at 80 the lower end of said central stem adapted to rest on the ground when the stem is inserted into the ground.

2. The machine gun recited in claim 1 together with a strap and means for securing 85 the strap to the rear portion of the gun.

In testimony whereof I affix my signature.
JACOBUS HENNEVELD.
